PORABLE DISHWASHING MACHINE

Walter I. Knapp, Detroit, Mich.

Application December 17, 1948, Serial No. 150,210

Term of patent 7 years

(Cl. D49—1)

To all whom it may concern:

Be it known that I, Walter I. Knapp, a citizen of the United States, residing in Detroit, county of Wayne, in the State of Michigan, have invented a new, original, and ornamental Design for a Portable Dishwashing Machine, of which the following is a specification, reference being made to the accompanying drawing, forming part thereof.

Fig. 1 is a top plan view of a portable dishwashing machine, embodying my new design.

Fig. 2 is a front elevational view thereof.

Fig. 3 is an elevational view of one end thereof.

Fig. 4 is an elevational view of the opposite end thereof.

The rear is substantially like the front.

I claim:

The ornamental design for a portable dishwashing machine, as shown and described.

WALTER I. KNAPP.
